MICHIGAN.

SHAPER GUARD.

Application filed May 27, 1926. Serial No. 112,182.

This invention relates to a guard device designed primarily for use in connection with the shaping element, of a shaping machine, but it is to be understood that a guard device, in accordance with this invention can be employed for any purposes for which it is found applicable, and the invention has for its object to provide, in a manner as herein-after set forth, a guard device including a 5 guard element and means controlled by a jig or the work on its travel to and from the shaper element to provide for the elevating and lowering of the guard element to and from guarding position with respect to the 10 shaper element under such conditions protecting the operator and reducing accidents to a minimum.

Further objects of the invention are to provide, in a manner as hereinafter set forth, 20 a guard device for the purpose referred to, which is simple in construction and arrangement, strong, durable, thoroughly efficient in its use, automatic in its operation, readily installed with respect to a shaping machine, 25 and comparatively inexpensive to set up.

With the foregoing and other objects in view, the invention consists of the novel construction, combination and arrangement of parts as hereinafter more specifically described and illustrated in the accompanying drawings, wherein is shown an embodiment of the invention, but it is to be understood that changes, variations and modifications 35 can be resorted to which fall within the scope of the claims hereunto appended.

In the drawings wherein like reference characters denote corresponding parts throughout the several views:

Figure 1 is a side elevation of a guard 40 device in accordance with this invention.

Figure 2 is a front elevation thereof.

Figure 3 is a top plan view thereof.

Figure 4 is an elevation of the circuit 45 opening and closing mechanism controlled by the jig or the work on its passage to and from the shaper element.

Referring to the drawings in detail, a 50 guard device, in accordance with this invention comprises a hood 1 of substantial height and which is in the form of a hollow cylinder open at its rear from top to bottom. The hood is constructed from a plate of sheet metal of the desired gage and bent in cylindrical form and with the opposed edges 55 of the plate spaced from each other so that

the hood will be open at the rear thereof. The hood 1 is termed a guard element, and is connected with a suitable means, to be presently referred to, for the purpose of elevating and lowering the guard element from 60 and to protecting position or guarding position with respect to the shaper element of a shaping machine. When the guard element 1 is in lowered position it acts as a hood to surround the shaper element. 65

The table or platform of the shaping machine is indicated at 2 and the guard element 1 is suspended a substantial distance thereabove and at a point to surround the shaper element, not shown, when the guard 70 element is in its lowered position. The table or platform 2 of the machine at a point forwardly with respect to the guard element 1 is provided with a vertically extending spring-controlled shifting element 3 for the 75 actuating lever of a circuit opening and closing mechanism, to be presently referred to, and which is arranged below the table or platform 2. The shifting element or device 3 projects a substantial distance above the 80 upper face of the table or platform 2 and is in the path of a jig which moves towards and from the shaper element of the machine. As the jig moves forwardly or rather towards 85 the shaping element of the machine the shifting device or element 3 is depressed and is held in such position as long as the jig is engaged with the top of the device 3. When the jig is moved clear of the upper end of the shifting device or element 3, the latter resumes its normal position, which is slightly projected above the upper face of the table or platform 2. The shifting device or element 3 can be of any suitable form. If the 90 work is shifted towards the shaping element, without the employment of the jig, then the work acts as a means to depress the shifting element or device 3 and maintains it in lowered or shifting position until the work is moved off therefrom. When the shifting device or element 3 is depressed, it provides 95 means for actuating the shifting lever of the circuit opening and closing mechanism for the purpose of closing a magnet or solenoid circuit to energize the same to cause the shifting of the means for elevating the guard element 1. When pressure is removed from the shifting device or element 3, the circuit opening and closing mechanism is restored to 100 normal position which provides for the open-

105

110

ing of the magnet or solenoid circuit and permits of the guard element 1 shifting downwardly to guarding or protecting position with respect to the shaper element of the machine.

Fixedly secured to the guard element 1 at a point in proximity to its upper end is a carrier 4 which extends around the outer face of the guard element 1 as well as being secured therewith, and projects rearwardly therefrom. The carrier 4 is in the form of a yoke, disposed horizontally, and has its arms project rearwardly from the guard element 1. Each of the arms of the carrier 4 has its rear free end in the form of a loop 7. The loops 7 are slidably mounted on a pair of spaced vertically disposed guide posts 8 arranged rearwardly of, spaced from and of greater height than the height of the guard element 1.

Secured to the guard element 1, in proximity to its lower end, is a combined guide and retaining member 9 of the same contour as the contour of the carrier 4 and said member 9 is slidably mounted, as at 10, on the posts 8.

Secured to the table or platform 2, by the hold fast devices 11 is a plate 12 having a concave forward edge 13 to provide a clearance for the collar lying under the shaper block. The guide posts 8 are secured into the plate 12. Jamb nuts 14 engage with the posts 8 and abut the plate 12. Mounted upon each of the nuts 14 and surrounding a post 8 is a vertically disposed sleeve 15, of appropriate height, and the said sleeves 15 provide stops for arresting the lowering movement of the guard element 1. The sleeves 15 are engaged by the rear ends of the member 9 for the purpose of arresting the lowering movement of the guard element 1, see Figure 1.

Arranged rearwardly of the posts 8, is an I-shaped standard 16 of less height than the height of said posts. The standard 16 is positioned centrally with respect to the space formed between the pair of posts 8, arranged rearwardly of the plate 12 and secured to the table 2 by the hold fast devices 17. The standard 16 is of greater height than the height of the guard element 1.

The upper ends of the posts 8 are connected together by a cross head or tie bar 18 and each end thereof is secured to the upper end of a post 8 by a pair of superposed nuts 19. Each end of the cross head or tie bar 18 is interposed between a pair of nuts 19. Secured to the top of the standard 16 is a pivot element formed of a pair of oppositely disposed bars 20, 21 and which project above the upper ends of the posts 8. Each of said bars has its lower end formed with a right angularly disposed flange 22 and its upper terminal portion offset as at 23. That part of the bars 20, 21 between

the upper terminal portions 23 and flanges 22 thereof, are arranged in abutting relation. Extending rearwardly from the cross head or tie bar 18 is a pair of brace members 24 which are disposed at a downward inclination and extend from the tie bar or cross head 18 to the flanges 22. The forward ends of the brace members 24 are secured to the cross head or tie bar 18 by the hold fast devices 25. The lower ends of the brace members 24 are seated on the flanges 22, and common to the lower ends of said brace members 24 and flanges 22 are hold fast devices 26 for fixedly securing the lower ends of the brace members and the flanges 22 to the upper end of the standard or support 16. The forward ends of the brace members 24 are angularly disposed with respect to the intermediate portions of said members and the lower ends of the members 24 are angularly disposed with respect to the intermediate portion of said members and in this connection see Figure 1. The offsetting of the upper terminal portions of the bars 20, 21 provide a harp, referred to generally by the reference character 27 for a purpose to be hereinafter set forth.

Supported by the pivot element which is formed by the oppositely disposed bars 20, 21 is an electrically controlled elevating and lowering mechanism for the guard element 1. The said mechanism includes a counter balanced lever arm 28 which is pivotally mounted in the harp 27 by the pivot bolt 29. The pivot bolt 29 is positioned slightly forward with respect to the transverse median of the lever arm 28 whereby the latter is eccentrically mounted on its pivot. The rear end of the lever 28 has adjustably mounted thereon a counter weight 30. The forward end of the lever arm 28 is pivotally connected, as at 31 between the upper ends of a pair of vertically disposed links 32. The lower ends of the links 32 are pivotally connected, as at 33, between a pair of oppositely disposed angle irons 34 which are fixedly secured as at 35 to the top of an inverted yoke 36. The arms of the yoke 36 are pivotally connected at diametrically opposite points to the carrier 4. Oppositely extending lugs 37 are provided on the carrier 4 which extend through the lower ends of the arms 38 of the yoke 36.

Adjustable on the standard 38' is a solenoid magnet 39 having its core indicated at 40 and which has its upper portion reduced. Pivotally connected as at 41 to the reduced upper end of the core 40 is a pair of opposed links 42. The lower ends of the links 42 are pivotally connected to the upper end of the core as at 41. The upper ends of the links 42 are pivotally connected as at 43 to the lever arm 28 rearwardly with respect to the pivot bolt 29. The links 42 are of non-conducting material.

From the construction aforesaid, when the solenoid 39 is energized, the core 40 thereof will move downwardly whereby the lever arm 28 will be shifted on its pivot and in a direction to elevate the guard element 1. When the solenoid 39 is de-energized, the guard element 1 will move downwardly by gravity, but its movement will be somewhat retarded by the weight 30. The position of the parts, when the magnet 39 is de-energized, is as illustrated in Figure 1.

The solenoid 39 has leading therefrom the circuit connections 44, 45 and which extend to a circuit opening and closing mechanism referred to generally by the reference character 46, Figure 4. Any suitable form of circuit opening and closing mechanism can be employed for opening and closing the solenoid circuit, and one form of circuit opening and closing mechanism is indicated at 46 and includes a contact member 47 to which the lead 44 is attached and a contact member 48 to which the lead 45 is attached. The contact member 47 is pivoted as at 49 and spring controlled through the medium of the spring 50. The contact member 48 is carried by a spring controlled pivoted lever 51. The circuit connection 45 is attached to the contact member 48. The controlling spring for the lever 51 is indicated at 52. The lever 51 is pivotally connected as at 53 to a pair of supports 54, carried by the casing 55 of the circuit opening and closing mechanism 46. The circuit closing and opening mechanism is electrically connected with a suitable source of energy. The lever 51 projects into the casing 55. The contact members 47, 48 are normally spaced from each other, but when the lever 51 is shifted on its pivot against the action of the controlling spring 52, the contact member 48 is brought into engagement with the contact member 47 thereby closing the solenoid circuit. The outer end of the lever 51 is formed with a flat extension 56, which is arranged in the path of the lower end of the spring controlled shifting device or element 3, see Figure 1. By this arrangement when the shifting device or element 3 is moved downwardly, the lower end of said device will engage the outer end of the lever 51 to shift the latter and provide for the closing of the circuit, and the circuit will remain closed as long as the shifting element or device is depressed or held in depressed position by the jig of the work.

The weight 30 acts as a counter balance and assists the electro-magnet or solenoid in the raising of the guard element and further checks the guard element from dropping too fast. The solenoid 39 is adjustably connected to the standard 38' as at 39'. The position of the solenoid 39 will control the distance in which the shield 1 is shifted

that is to say the lower the solenoid 39 the higher the shield 1 will be lifted.

As the elements of the guard device with the exception of the spring controlled lever 51, are free of controlling springs or do not have associated therewith controlling springs, their operation is not affected in any manner by shavings or sawdust and further the device is so set up that the guard element or shield is not shifted from protecting position unless the jig or work depresses or bears on the shifting device or element 3. Furthermore unless the solenoid circuit is closed, the guard element 1 is never elevated from protecting position with respect to the shaver element.

It is thought the many advantages of a guard device, in accordance with this invention for the purpose referred to, can be readily understood, and although the preferred embodiment of the invention is as illustrated and described, yet it is to be understood that changes in the details of construction can be had which will fall within the scope of the invention as claimed.

What we claim is:

1. A guard device for the purpose set forth comprising a guard element vertically movable to and from guarding position with respect to a shaper element, and an electrically operated counter-balanced lever mechanism for shifting said guard element from and to guarding position with respect to the shaper element, said mechanism controlled by the passage of the work to and from the shaper element.

2. A guard device for a shaper element comprising a guard element in the form of a hood and vertically movable from and to guarding position with respect to the shaper element, a counter-balanced lever mechanism connected to said guard element, and electrical means controlled by the passage of the work to and from the shaper element for operating said lever mechanism to shift the guard element from guarding position with respect to the shaper element and for maintaining the guard element in non-guarding position when the shaper element is active on the work, said guard element shifting by gravity to guarding position by the opening of the circuit for said electrical means.

3. A guard device for a shaper element comprising a guard element normally surrounding, when in guarding position, the shaper element, said guard element vertically movable from and to guarding position, a counter-balanced lever mechanism adapted when operated in one direction to shift said guard element from guarding position with respect to the shaper element, electrical means normally in an open circuit and connected with said mechanism and further adapted to operate the latter when the cir-

cuit for said means is closed to shift the guard element from guarding position with respect to the shaper element, and means operated by the passage of the work toward the shaper element for closing the circuit for said electrical means to shift the guard element from guarding position and for maintaining it in non-guarding position during the activity of the shaper element on the work.

4. A guard device for a shaper element comprising a guard element in the form of a hood and vertically movable from and to guarding position with respect to the shaper element, a counter-balanced lever mechanism connected to said guard element, electrical means controlled by the passage of the work to and from the shaper element for operating said lever mechanism to shift the guard element from guarding position with respect to the shaper element and for maintaining the guard element in non-guarding position when the shaper element is active on the work, said guard element shifting by gravity to guarding position by the opening of the circuit for said electrical means, and guiding means for said guard element.

5. A guard device for a shaper element comprising a guard element normally surrounding, when in guarding position, the shaper element, said guard element vertically movable from and to guarding position, a counter-balanced lever mechanism adapted when operated in one direction to shift said guard element from guarding position with respect to the shaper element, electrical means normally in an open circuit and connected with said mechanism and adapted when its circuit is closed to operate said lever mechanism to shift the guard element from guarding position with respect to the shaper element, means operated by the passage of the work toward the shaper element for closing the circuit for said electrical means to shift the guard element from guarding position and for maintaining it in non-guarding position during the activity of the shaper element on the work, and guiding means for said guard element.

6. A guard device for a shaper element comprising a guard element in the form of a hood and vertically movable from and to guarding position with respect to the shaper element, a counter-balanced lever mechanism connected to said guard element, electrical means controlled by the passage of the work to and from the shaper element for operating said lever mechanism to shift the guard element from guarding position with respect to the shaper element and for maintaining the guard element in non-guarding position when the shaper element is active on the work, said guard element shifting by gravity to guarding position by the opening of the

circuit for said electrical means, guiding means for said guard element, and means for limiting the movement of the guard element when shifting to guarding position.

7. A guard device for a shaper element comprising a guard element normally surrounding, when in guarding position, the shaper element, said guard element vertically movable from and to guarding position, a counter-balanced lever mechanism adapted when operated in one direction to shift said guard element from guarding position with respect to the shaper element, electrical means normally in an open circuit and connected with said mechanism and adapted when its circuit is closed to operate said lever mechanism to shift the guard element from guarding position with respect to the shaper element, means operated by the passage of the work toward the shaper element for closing the circuit for said electrical means to shift the guard element from guarding position and for maintaining it in non-guarding position during the activity of the shaper element on the work, guiding means for said guard element, and means for arresting the movement of the guard element when shifting to guarding position.

8. A guard device for a shaper element comprising a guard element in the form of a hood for surrounding the shaper element when said guard element is in guarding position, a lever mechanism for shifting said guard element from guarding position with respect to said shaper element, said guard element movable to guarding position by gravity, and electrical means controlled by the passage of the work to the shaper element for operating said lever mechanism to shift the guard element from guarding position and further to maintain said guard element in non-guarding position during the activity of the shaper element on the work.

9. A guard device for a shaper element comprising a guard element in the form of a hood for surrounding the shaper element when said guard element is in guarding position, a lever mechanism for shifting said guard element from guarding position with respect to said shaper element, said guard element movable to guarding position by gravity, electrical means controlled by the passage of the work to the shaper element for operating said lever mechanism to shift the guard element from guarding position and further to maintain said guard element in non-guarding position during the activity of the shaper element on the work, and guiding means for said guard element.

10. A guard device for a shaper element comprising a guard element for surrounding the shaper element when in inactive position, said guard element vertically movable from and to guarding position, said guard element movable to guarding position

by gravity, elevating means for said guard element to shift the latter from guarding position, electrical means for operating said elevating means, said electrical means normally in an open circuit, and means acted upon by the work by its passage towards the shaper element for closing the circuit of said electrical means to provide for the operation for said elevating means to shift the guard element from guarding position and to maintain the latter in non-guarding position during the activity of the shaper element on the work.

11. A guarding device for a shaper element comprising a guard element for surrounding the shaper element when in inactive position, said guard element vertically movable from and to guarding position, said guard element movable to guarding position

by gravity, elevating means for said guard element to shift the latter from guarding position, electrical means for operating said elevating means, said electrical means normally in an open circuit, means acted upon by the work by its passage towards the shaper element for closing the circuit of said electrical means to provide for the operation of said elevating means to shift the guard element from guarding position and to maintain the latter in non-guarding position during the activity of the shaper element upon the work, and guiding means for said guard element.

In testimony whereof, we affix our signatures hereto.

MARTIN A. GRIMORD.
ADOLPH P. GRIMORD.
